POLYVALENT ORGANO-LEAD FUNGICIDE
 Waldo B. Liggett, Pontiac, Mich., assignor to Ethyl Corporation, New York, N.Y., a corporation of Virginia
 No Drawing. Filed July 10, 1961, Ser. No. 122,660
 14 Claims. (Cl. 167—22)

This invention relates to fungicidal compositions, and more particularly to new and potent lead-containing fungicidal compositions and their use in combatting fungi.

An object of this invention is to provide new fungicidal compositions. A further object is to provide new fungicidal compositions comprising conditioning agents and certain organolead salts as described herein. Still another object is to provide new means and methods for combatting fungi.

The above and other objects are accomplished by the present invention which in part resides in providing fungicidal compositions comprising a conditioning agent and, as a principal active fungicidal ingredient, a particular type of organolead salt containing 2 to 3 organo groups. The organolead salts in question have the formula

wherein R_1 and R_2 are alkyl or aryl groups, wherein R_3 is alkyl, aryl or Anion, and wherein Anion is a member of the group consisting of chlorophenate anions, arenesulfonamide anions, thiosalicylate anion, acetate anion, haloacetate anions, dihydrogen phosphate anion, and arsanilate anion. R_1 , R_2 and R_3 are not necessarily the same. Preferably the alkyl groups each contain up to about 8 carbon atoms. The aryl groups preferably contain 6 to about 12 carbon atoms and are phenyl, alkyl-substituted phenyl, naphthyl and alkyl-substituted naphthyl groups. Generally, the dialkyllead and trialkyllead salts of the foregoing formula have greater potency against most common fungi than do the above diaryllead and triaryllead salts and for this reason these alkyllead salts can and preferably are used at lower concentrations in combatting or controlling fungi especially those that infest vegetation. It will be a simple matter in the light of this description to determine the optimum concentration of my fungicides for all intended uses and applications.

The chlorophenate anions of my novel fungicidal compositions can contain one, two, and preferably, three, four or five chlorine atoms. The nucleus of the phenoxy group can be additionally substituted with lower alkyl groups—preferably methyl, ethyl, propyl or butyl groups—when there are less than five chlorine substituents on the ring. Particularly effective are the di- and triorganolead pentachlorophenates. Illustrative examples of the organolead chlorophenate salts used as fungicides pursuant to this invention include triethyllead chlorophenate (o-, m-, p-chloro isomers, or mixtures of these), triethyllead-2,4-dichlorophenate, the triethyllead tetrachlorophenates, triethyllead pentachlorophenate, diethyllead di-(2,5-dichlorophenate), dimethyllead di-(2,4,5-trichlorophenate), dibutyllead di-(p-chlorophenate), tri-2-ethylhexyllead-2,4,6-trichlorophenate, diisopropyllead di-(2-methyl-6-chlorophenate), diamyllead di-(pentachlorophenate), tri-2-octyllead-2-chloro-4-tert-butylphenate, diphenyllead di-(2,4,5-trichlorophenate), tri-p-tolyllead-o-chlorophenate, tri-p-cumyllead-2,5-dichlorophenate, naphthylethylead di-(m-chlorophenate), and the like. As pointed out above the pentachlorophenates are particularly preferred because of their very great effectiveness as fungicides.

The arenesulfonamide anions of the present fungicides

2

preferably contain from 6 to about 10 carbon atoms in the arene group. Examples of these compounds are triethyllead-p-toluene sulfonamide, diethyllead di-(p-toluene sulfonamide), tripropyllead benzene sulfonamide, trihexyllead-p-cumene sulfonamide, dioctyllead di-(2,4-xylene sulfonamide), trixyllead-p-toluene sulfonamide (mixed xylyl isomers), diphenyllead di-(benzene sulfonamide), and the like. The di- and triorganolead arenesulfonamides are preferred for use in this invention because of their relatively low phytotoxicity against such common crops as cotton and soybeans.

Examples of my di- and triorganolead thiosalicylate fungicides include triethyllead thiosalicylate, triheptyllead thiosalicylate, dimethyllead di-(thiosalicylate), methylphenyllead di-(thiosalicylate), tri-m-tolylead thiosalicylate, di-2,5-xylyllead di-(thiosalicylate), and the like. A preferred feature of these compounds is their relatively low phytotoxicity against such crops as cucumbers and soybeans.

Illustrative examples of my di- and triorganolead acetate fungicides are triethyllead acetate, trimethyllead acetate, diethyllead diacetate, dibutyllead diacetate, tributyllead acetate, triphenyllead acetate, diphenyllead diacetate, di-(2,5-diethylphenyl)lead diacetate, and the like. 20 25 An advantageous and preferred characteristic of these di- and triorganolead acetates is their relatively low phytotoxicity against such abundant crops as corn and wheat. Moreover, these compounds can be readily prepared at relatively low cost, and these factors, together with their 30 considerable fungicidal potency render the acetates especially preferred for use in this invention.

The haloacetate anions of my novel fungicidal compositions can contain 1, 2 or 3 halogen atoms in the acetate radical, these halogens being bromine, iodine, and 35 preferably chlorine or fluorine. Mixtures of these halogen atoms can also be present. Specific examples of these fungicides include triethyllead trichloroacetate, triethyllead trifluoroacetate, diethyllead di-(monochloroacetate), dimethyllead di-(monochloroacetate), tributyllead dichloroacetate, trihexyllead dichlorofluoroacetate, triphenyllead trichloroacetate, dicamyllead di-(monofluoroacetate), phenyldiethyllead tribromoacetate, diamyllead di-(moniodoacetate), and the like. These compounds are preferred for use in this invention because of their relatively low phytotoxicity against such plant species as soybeans.

Examples of my di- and triorganolead dihydrogen phosphate fungicides include triethyllead dihydrogen phosphate, trioctyllead dihydrogen phosphate, triphenyllead dihydrogen phosphate, diethyllead bis-(dihydrogen phosphate), di-o-tolyllead bis-(dihydrogen phosphate), octyl-dimethyllead dihydrogen phosphate, and the like.

Exemplary of my di- and triorganolead arsanilate fungicides are triethyllead arsanilate, tri-sec-butyl arsanilate, triphenyllead arsanilate, triamyllead arsanilate, dimethyllead diarsanilate, di-2,4-xylyllead diarsanilate, phenyl-p-tolyllead diarsanilate, and the like. An advantage of these compounds is their relatively low phytotoxicity as regards such crops as soybeans.

60 Another facet of this invention is my novel method of controlling and combatting fungi. Accordingly, one embodiment of this invention is the method of combatting fungus which comprises contacting the fungus with a phytotoxic amount of a compound having the formula given above. Another aspect of my invention is the provision of a method for controlling fungi which comprises treating matter susceptible to infestation by such organisms with a compound of the above formula.

The conditioning agents with which I admix my active fungicidal ingredients are of the type known to the art as substantially inert fungicidal adjuvants. These comprise a dispersant and a surface active agent. The pur-

pose of these materials is to extend the active fungicidal ingredient to insure its efficacious penetration into or application onto the locus being treated and to adapt the active fungicidal ingredients for ready and efficient application to pests and to the loci of the fungi using conventional equipment. In general such formulations comprise both the liquid and solid types as well as the "Aerosol" type of formulation. The liquid type of formulation can have water, an organic solvent, an oil-water emulsion and the like as the conditioning agent. The liquid ingredient of the formulation may further contain a surface active agent such as a detergent, a soap or other wetting agent. It is also intended that the term "conditioning agent" include solid carriers such as talc, pyrophyllite, Attaclay, kieselguhr, chalk, diatomaceous earth, and the like; and various mineral powders such as calcium carbonate and the like which act as a dispersant, as a carrier, and in some instances perform the function of a surface active agent. Among the preferred formulations employing solid conditioning agents are those known as wettable powders. In general these wettable powders include the active ingredient, a surface active agent and an inert carrier such as soybean flour, sulfur, calcium oxide, mica, talc, humus and the like. In preparing such concentrated wettable powders it is preferred to employ between about 0.1 and 5 percent of the surface active agent based upon the amount of active fungicidal ingredient used and up to about 85 percent of the inert solid carrier based upon the total amount of the formulation. Such formulations provide the advantage of permitting storage and transportation of the pesticides in readily handled form and permit further dilution by simple admixture with water to provide finished liquid formulations at the time of application.

Thus the formulations which comprise my active ingredient in combination with a conditioning agent provide liquid, solid and aerosol formulations in a form adapted to be readily applied to the material to be treated. The liquid compositions, either solutions or dispersions, frequently contain a surface active dispersing agent in amount sufficient to render the composition readily dispersable in water for aqueous spray application. The solid formulations also frequently contain a surface active dispersing agent in amount sufficient to impart water dispersibility to the compositions. When dust application is desired a surface active dispersing agent can be omitted. In this case the formulation will still contain a solid carrier, extender or diluent as conditioning agent.

The surface active dispersing agents referred to herein are sometimes known as wetting, dispersing or penetrating agents. They are agents which cause the formulations to be easily dispersed in water. They can be of the anionic, cationic or non-ionic type and include salts of long chain fatty acids, sulfonated oils—both vegetable and animal—petroleum oils, sulfates of long chain alcohols, phosphates of long chain alcohols, various polyethylene oxides and condensation products of ethylene oxide with alcohols and phenols, quaternary ammonium salts and the like. The surface active agent will usually be present to the extent of 0.1 to 5 percent of the formulation.

The active ingredients can also be dispersed or suspended in various organic solvents such as alcohols, ketones, hydrocarbons, petroleum cuts such as kerosene, dimethylformamide and the like. In this case a surface active dispersing agent is usually present to provide ready dispersibility with water.

To illustrate certain of the formulations employed, I mix 50 parts of tributylead acetate with 50 parts of diatomaceous earth and 3 parts of sodium lauryl sulfate and then grind the mixture to obtain a wettable powder formulation suitable for dilution with water. I also mix 30 parts of diisopropyllead di-(pentachlorophenate) with 500 parts of fuller's earth to obtain a dust formulation suitable for application.

To obtain a liquid concentration I mix 50 parts of triphenylead p-tert-butylbenzene sulfonamide with 50 parts of kerosene and 2 parts of cetyltrimethylbenzylammonium chloride as a wetting agent. To make oil-water emulsion from this formulation I add it with vigorous stirring to 400 parts of water.

Other formulations comprising active ingredients of this invention together with conditioning agents are prepared by similar means and have in general make-ups similar to those given above.

In general all my finished formulations, depending upon the application in mind, usually contain between about 0.1 to 10,000 p.p.m. of active ingredient. A preferred range for agricultural application is between 0.1 and 2,000 p.p.m. In other applications such as in wood treating, plastics, paper and textiles the amount of active ingredient may be higher than 2,000 p.p.m.

The fungicidal effectiveness of my compounds can be demonstrated by the following test.

Slide germination test.—By the slide germination test the concentration of the chemical required to inhibit germination of spores from 7- to 10-day old cultures of *Alternaria oleracea* and *Sclerotinia fructicola* is determined. Concentrations of active ingredients used in this test are 1000, 100, 10, and 1.0 p.p.m. The specified concentrations of active ingredient are prepared in aqueous suspension by a series of test tube dilutions. Following the initial dilutions, four volumes of suspension are diluted with one volume of spore stimulant and spore suspension. The spore stimulant is added to insure a high and relatively stable percentage of germination in the checks. Drops of the test suspension mixture, and an untreated control are pipetted onto glass slides. The glass slides are placed in moist chambers for 20 hours' incubation at 22° C. Germination counts are made by counting 100 potentially viable spores, those spores that would germinate under the normal conditions of the control. The percent germination is expressed by the following equation: observed percent germination $\times 100 \div$ percent germination in the control. Test compounds are given letter ratings which correspond to the concentration that inhibits germination of half of the spores (ED₅₀): AA=0.1 to 1.0 p.p.m.; A=1.0 to 10 p.p.m.; B=10 to 100 p.p.m.; C=100 to 1000 p.p.m.; and D=>1000 p.p.m. The glass slide germination test by the test tube dilution method is adapted from a procedure recommended by the American Phytopathological Society's committee on standardization of fungicidal tests. (Phytopathology 37, 354-356 (1947).)

In such a test typical fungicides of my invention gave the following results:

	Organolead Salt	Slide Germination	
		A.o.	S.f.
55	Triethyllead dihydrogen phosphate	A-	A
	Triethyllead pentachlorophenate	AA-	AA-
	Triethyllead p-toluenesulfonamide	B	A
	Triethyllead trichloroacetate	B	AA
	Triethyllead thiosalicylate	B	A
60	Triethyllead arsenite	B-	A
	Triethyllead acetate	B	AA-

In the above table a minus sign indicates the average results of two tests where the determinations varied by one rank. For example, a rating of "AA—" shows that in one determination the compound had an "AA" rating while in another it had an "A" rating. The results shown in the above table are merely illustrative since the results obtained when using other organolead salts of the type described herein (e.g., the corresponding diorganolead salts) are very similar. Similar results are also obtained when active ingredients are formulated with the conditioning agents of the type illustrated herein.

A particular advantage of the present fungicides is my finding that in addition to being exceedingly potent

against fungi they have considerable potency as insecticides. Moreover, as brought out above the present fungicides are especially useful for agricultural applications since the vast majority of my fungicides are inherently relatively non-phytotoxic as regards various commercially important crops, especially at my recommended low use concentrations. Where it is desired to provide a general all-purpose agricultural fungicide it is preferable to employ my di- and triaryllead salts since these appear to be even less phytotoxic than my alkyllead salts. On the other hand, my alkyllead salts are preferred for specific foliage-protectant fungicidal applications because of their generally greater fungicidal potency.

My fungicides can be prepared by known methods. For example, to prepare my organolead chlorophenate fungicides the appropriate tetraorganolead compound (e.g., tetraethyllead, tetraamyllead, tetraphenyllead, etc.) is reacted with the desired chlorophenolic compound at a temperature in the range of about 75-175° C. in an inert organic solvent using a catalyst such as silica gel. My organolead arenesulfonamides can be prepared by the procedure described by B. C. Saunders, J. Chem. Soc., 1950, 684-7. My organolead thiosalicylate fungicides may be prepared by making use of the procedure described by H. Gilman and J. D. Robinson, Rec. trav. chim., 49, 766-8 (1930). To prepare my organolead acetate and organolead haloacetate fungicides recourse may be had to the procedures exemplified by A. K. Kochetkov and R. Kh. Freidlina, Uchenye Zapiski Moskov. Gosudarst. Univ. M. V. Lomonosova, No. 132, Org. Khim. No. 7, 144-50 (1950). Methods for preparing my organolead dihydrogen phosphate fungicides are typified by the procedure described by Klippel, J. prakt. Chem. [1] 81, 286 (1860.) To form my organolead arsanilate fungicides generally similar procedures are used, e.g., condensation of the appropriate organolead hydroxide with arsanilic acid.

I claim:

1. A fungicidal composition comprising as a principal active ingredient an organolead salt having the formula

wherein R_1 and R_2 are selected from the group consisting of alkyl groups containing up to about 8 carbon atoms and aryl groups containing from 6 to about 12 carbon atoms, wherein R_3 is selected from the group

consisting of alkyl groups containing up to about 8 carbon atoms, aryl groups containing from 6 to about 12 carbon atoms and Anion, and wherein Anion is a member of the group consisting of chlorophenate anions, arenesulfonamide anions, thiosalicylate anion, acetate anion, haloacetate anions, dihydrogen phosphate anion, and arsanilate anion; and, as a carrier therefor, a substantially inert fungicidal adjuvant comprising a dispersant and surface active agent.

2. The composition of claim 1 further characterized in that said ingredient is a diaryllead salt as defined therein.

3. The composition of claim 1 further characterized in that said ingredient is a triaryllead salt as defined therein.

4. The composition of claim 1 further characterized in that said ingredient is a dialkyllead salt as defined therein.

5. The composition of claim 1 further characterized in that said ingredient is a trialkyllead salt as defined therein.

6. The composition of claim 1 further characterized in that said ingredient is a dialkyllead diacetate.

7. The composition of claim 1 further characterized in that said ingredient is a trialkyllead acetate.

8. The method of combatting fungus which comprises contacting the fungus with a phytotoxic amount of an organolead salt as defined in claim 1.

9. The method of claim 8 further characterized in that said salt is a diaryllead salt.

10. The method of claim 8 further characterized in that said salt is a triaryllead salt.

11. The method of claim 8 further characterized in that said salt is a dialkyllead salt.

12. The method of claim 8 further characterized in that said salt is a trialkyllead salt.

13. The method of claim 8 further characterized in that said salt is a dialkyllead diacetate.

14. The method of claim 8 further characterized in that said salt is a trialkyllead acetate.
